FREDERIC S. CONVERSE, OF LYONS, NEW YORK.

EXTENSION COAL-CHUTE.

No. 827,349.

Specification of Letters Patent.

Patented July 31, 1906.

Application filed March 31, 1906. Serial No. 309,101.

To all whom it may concern:

Be it known that I, FREDERIC S. CONVERSE, a citizen of the United States, residing at Lyons, in the county of Wayne and State of New York, have invented certain new and useful Improvements in Extension Coal-Chutes, of which the following is a specification.

This invention relates to chutes such as are commonly employed in connection with coal-wagons for the purpose of delivering the coal automatically from the wagon into a bin, a hole in the pavement, a window, or elsewhere; and the object of the same is to improve the construction of such chutes.

To this end the invention consists in the structural features of the chute-sections, the support for the upper end of the chute, the couplings between the sections, and a shield for protecting the window-frame or other object surrounding the aperture into which the coal is delivered, all as hereinafter more fully described and as shown in the accompanying drawings, wherein—

Figure 1 is a perspective view of two sections of this chute set up ready for use. Fig. 2 is a cross-section on the line 2 2 of Fig. 1. Fig. 3 is an upper end view on the line 3 3 of Fig. 1, showing two sections nested. Fig. 4 is an enlarged longitudinal section to illustrate more particularly the coupling. Fig. 5 is an enlarged perspective detail. Fig. 6 is a sectional detail on the line 6 6 of Fig. 1.

The principal parts of this device are the chute-sections C, with their lips L, the coupling devices H, the support X, and the shield S. Each chute is constructed of sheet-iron, with a body I, which may be tapering or otherwise, having longitudinal corrugations 2 for the purpose of giving it strength, raised sides 3, beaded at their upper edges, as at 4, and reinforcing-straps 5, passing transversely across beneath the ends of the section, turned upward outside of the sides 3 and over the beading and securely riveted thereto, as at 6. The proportion of parts is immaterial, and the length and width thereof will depend upon circumstances. The degree of taper is such that when the sections are telescoped one will be almost completely nested within the next, and with the object of assembling the sections into as small a space as possible for the purpose of storage and transportation I have constructed all parts on the basis that

when folded or out of active use they shall not interfere with the close nesting of the sections themselves.

At the upper end of each section there is a transverse lip L. This may be formed integrally with the bottom I by turning it down, as at 10 in Fig. 1; but by preference it is a sheet of L-iron 11, bolted or riveted beneath the bottom, as best seen at 120 in Fig. 4, and this lip is provided with two longitudinal slots 12 for the reception of the legs and coupling members described below. A web 13 is preferably left between these slots (rather than continuing them across any one slot) for the purpose of increasing the rigidity of the lip, which serves as a brace to prevent the buckling or bending of the bottom of the chute under a heavy load or rough usage.

The coupling H between the sections consists of two hooks 20, taking over the beading 4 of the upper section, and means whereby these hooks are adjustably connected with the lip of the lower section while yet standing outside the chute, so as not to interfere with the passage of coal.

From the illustration in Fig. 1 it will be clear that the weight of the coal at the junction of the two sections will bear downward on the lower end of the upper section and give the upper end of the lower section a tendency to drop from beneath the body of the upper section. This tendency it is my purpose to overcome by a coupling device standing outside the chute, and as it is the smaller end of the upper section which here laps into the larger end of the lower section it will be seen that the coupling must be adjustably connected with the lower section in order to accommodate it to the width of that point of the upper section, which width is determined by the degree of the lap. Heretofore various couplings have been used at this part; but no device which is permanently connected at a certain point with one section can be self-adjusting when telescoped into or out of another section without obstructing the flow of coal. Each coupling H (see Fig. 4) preferably comprises a hook 20 about two links 21, a traveling connector 22, (which itself may have a hooked lower end 23, extending under the lip L for keeping the traveling connector 22 in an upright position at all times, and also may sustain part or all of the strain on the coupling,) and a connec-

tion, such as a bolt 24 or the like, taking into the slot 12, which bolt 24 or the like may sustain part or all of the strain on the coupling. This connection may be a rivet loosely 5 engaging the slot, so that the traveling connector 22 can move, or may be a bolt or the like which might have a thumb-nut, as seen in Fig. 4, or the traveler may be a link connection.

- 10 When the sections are set up, the hooks 20 are engaged over the beading 4 and the traveling connectors 22 naturally adjust themselves to the proper position beneath, so that the entire coupling H stands vertical. In 15 order to store away the couplings H and prevent their rattling when not in use, I may provide keeper-hooks 25, pivoted in the upper end of each section to engage the hooks 20, as best seen in Fig. 5, this form of keeper 20 holding the couplings at the outer extremities of the slots 12, so as not to interfere with nesting the next section above.

While the chutes are generally employed in connection with coal-wagons, occasions 25 often arise where they must be otherwise supported. I have therefore devised the support X, (best seen in Fig. 1,) which consists of two legs 30, preferably pivoted at 31, where they cross each other, and having hooked upper ends 32, (or the legs may be connected together in any other suitable form.) The latter take into slots 12 when in use, and, if necessary, the traveling connectors of the uppermost couplings could be approximated 30 and their nuts 24 tightened in the slots 12, so as to hold the hooked upper ends 32 of the legs at a proper position to raise the support as might be desired. When not in use, this support can be turned back beneath the 40 chute-section or can be detached entirely at will. When coal is unloaded from a wagon and into a basement-window, the building just above the chute is frequently dirtied and disfigured with the coal. In order 45 to prevent such disfigurement, I provide an adjustable shield S. (Best seen in Fig. 1.) This preferably consists of a U-shaped rod 40, adapted to be passed through strap-eyes 41, which are riveted to the outer sides of the 50 section, and a metal plate 42, having eyes 43 struck up from its body or otherwise formed thereon and adjustably engaging the legs of the rod 40. The eyes 41 are placed at such position on each section that if one of these 55 shields S is employed on the lowermost section the building just above the chute will be protected, and the result is that if the deliveryman permits the coal to flow too fast it will bank up against the shield, but cannot 60 injure the building.

All parts of this device are preferably of metal, and, as stated above, sizes and proportions and exact details are immaterial. The uses of the various features have been 65 explained in connection with their descrip-

tion and need not be repeated here. However, it may be well to call attention to the fact that the peculiar form of coupling employed not only permits the lapping of the sections to the degree desired, but allows one 70 section to be set at an angle to another, as when the entire chute must deliver around an intervening obstruction. The legs of the rod 40 by reason of passing through the strap-eyes 41 and the upper end leaning 75 against the building and the lower ends being supported prevents the chute from slipping ahead.

What is claimed as new is—

1. A coal-chute made in sections adapted 80 to telescope into each other, combined with couplings adjustably secured to the upper end of each section and adapted to engage the section above.

2. A coal-chute made in sections adapted 85 to telescope into each other, reinforcing straps at the ends of each section, and a lip at the upper end of each section; combined with traveling connectors adjustably secured to said lip, and hooks carried by the traveling 90 connectors and adapted to engage with other sections.

3. A coal-chute made in tapering sections, and a lip at the upper end of each section; combined with traveling connectors having 95 hooked lower ends movably engaged beneath said lip, and means carried by the traveling connectors for engaging with other sections.

4. A coal-chute made in tapering sections, and a lip at the upper end of each section provided 100 with transverse slots; combined with traveling connectors engaging said lip, bolts or the like in the traveling connector taking loosely through said slots, and means carried by the traveling connector for engaging with 105 other sections.

5. A coal-chute made in tapering sections, and a lip at the upper end of each section provided with transverse slots; combined with traveling connectors having hooked lower 110 ends engaging beneath the lip, bolts or the like through the traveling connectors loosely 115 engaging said slots, and means carried by the traveling connectors for engaging with other sections.

6. A coal-chute made in tapering sections and a lip at upper end of each section provided with transverse slots; combined with traveling connectors, bolts or the like to hold the traveling connectors loosely engaged in 120 said slots, hooks adapted to engage with other sections, and links flexibly connecting the hooks with their respective traveling connectors.

7. In a coal-chute made in sections, the 125 combination with a lip at the upper end of each section, and keeper-hooks within its side walls; of couplings comprising traveling connectors movably attached to said lips and hooks flexibly connected with their respec- 130

tive traveling connectors and adapted to be engaged by said keepers, for the purpose set forth.

8. A coal-chute section having a lip at its upper end provided with transverse slots, combined with a support consisting of legs having hooked upper ends loosely engaging said slots.

9. A coal-chute section having a lip at its upper end provided with transverse slots, combined with a support consisting of legs having hooked upper ends loosely engaging said slots, and keepers having bolts adjustably engaging said slots outside said hooks, for the purpose set forth.

10. A coal-chute section having eyes on the outer faces of its side walls, combined with an adjustable shield extending across and above the section, and legs thereon relatively movably engaging said eyes.

11. A coal-chute section having eyes on the outer faces of its side walls, combined with an adjustable shield extending across and above the section, and itself having eyes, and an inverted-U-shaped rod whose legs pass through the eyes in the shield and adapted to enter the eye on the section. 25

12. A coal-chute made in tapering sections, combined with couplings adapted to connect two sections and to move lengthwise of the upper section and crosswise of the lower section by adjustably engaging the end of the lower section, substantially as described. 30

In testimony whereof I affix my signature in presence of two witnesses.
